UNITED STATES PATENT OFFICE.

HERBERT H. HULL, OF CLEVELAND, OHIO.

MECHANISM FOR WIRING CAN-CAPS.

SPECIFICATION forming part of Letters Patent No. 634,112, dated October 3, 1899.

Application filed December 29, 1898. Serial No. 700,578. (No model.)

To all whom it may concern:

Be it known that I, HERBERT H. HULL, a citizen of the United States, residing at Cleveland, in the county of Cuyahoga and State of Ohio, have invented a certain new and useful Improvement in Mechanism for Wiring Can-Caps and the Like, of which the following is a full, clear, and exact description, reference being had to the accompanying drawings.

10 The object of the invention is to secure a rippling-wire in the edge of can covers or caps or like articles by rolling the edge of the flange of said cap inward around the wire and to effect this result expeditiously and cheaply.

15 The invention is adapted for use with well-known forms of presses commonly employed for stamping sheet metal.

The invention relates particularly to the wiring-die and to the mechanism for properly feeding the wire thereto and for cutting off the outer end of said wire; and it consists in the construction and combination of parts hereinafter described, and definitely pointed out in the claims.

25 The drawings clearly disclose my invention embodied in a complete die-press.

Figure 1 is a front elevation of such press. Fig. 2 is a side elevation thereof, and Fig. 3 a sectional plan thereof just above the die. 30 These views are on the same scale. Fig. 4 is a side elevation of the reversing mechanism of the wire feed shown in the preceding figures on a smaller scale. Fig. 5 is a section on line 5 of Fig. 4, looking in the direction 35 of the arrow. Figs. 6 and 7 are side elevations on a larger scale than Fig. 1 or 2 of the cams on the power-shaft for operating the wire-feed and wire-cut-off mechanisms, respectively. Figs. 8 and 9 are vertical central 40 sections through the wiring-die and the lower end of the plunger, the former figure showing the parts when the plunger in its descent is just about to curl the can-cover around the wire and the latter figure showing such operation just completed, the plunger being at the extreme lower end of its travel. Fig. 10 is a horizontal section on the line 10 of Fig. 8, illustrating the manner of cutting off and bending the wire, the final position of 45 the wire at the end of the operation being indicated by dotted lines. Fig. 11 is a perspective view of the inner portion of the cut-off

lever. These four figures are all on the same scale and are of an actual size which would frequently occur in practice. Fig. 12 (on the 55 same sheet with Fig. 1) is a perspective view of the wired can-cover, the projecting end of the wire being bent back toward the cover, as shown.

Referring to the parts by letters, X represents the bed-plate of a suitable press, Y the vertical reciprocating plunger thereof, and Z a shaft by which the plunger is reciprocated. These parts, as shown, are of well-known 60 form.

The wiring-die is secured upon the bed-plate under the plunger, which plunger carries a pressure-plate C, by means of which the cap R is forced downward, with the results to be presently described.

70 The wiring-die includes an outer ring A, an expanding ring B, inside the ring A, made up of several segment-shaped parts b, the rod E, and a sleeve D, of which said sleeve carries beveled surfaces which operate on the 75 ring-sections to expand and contract them and the rod E carries suitable shoulders for operating the sleeve D.

The outer ring A may be secured to a suitable frame a, by means of which it is secured 80 upon the bed-plate. This ring A at its upper end is of a size and shape which causes the flange r of the cap R to snugly fit it. A short distance below this ring has an internal circumferential rib a, and on top of 85 this rib there is an annular curling-groove a', which is substantially semicircular in vertical section, the outer wall of this groove being a continuation of the inner wall of the ring A.

90 The expanding ring B is made up of a plurality of sections b, which when the ring is circular, as shown, are substantially quadrant-sectors. On the upper and lower outer edge of these ring-sections are the two flanges 95 b' b'', of which the former passes over and the latter passes under the rib a when the parts are assembled. In other words, the rib a lies between these flanges and very close to both, whereby any substantial vertical movement 100 of the sections is prevented. Pins a² projecting radially inward from the rib a enter the corresponding holes in the outer edges of the ring-sections, whereby said sections are guided

in their movements toward and from the center. The upper flange b' should be nearly as wide as the top of the rib a , wherefore when the ring B is expanded the distance between 5 the edges of said flanges and the inner wall of the ring A shall be less than the diameter of the wire to be used. This prevents the wire from passing up between the flange and the ring A . The expanding ring has a central hole through it, and the lower edge b^3 of this hole is beveled outward more or less. Surrounding this hole on the top of the expanding ring is an annular groove b^4 , the inner edge of which is beveled up to the 15 hole, thereby forming a substantially conical wedge b^5 .

The sleeve D passes centrally through the expanding ring. Its body, as shown, is cylindrical, and must be so large that if the ring-sections b embraced it the ring B would be expanded. It may, however, be of larger diameter and is so shown. The upper end or neck d of this sleeve is of reduced size, whereby when this neck is embraced by ring-sections b the ring B may be contracted. The shoulder d' where the neck and body join is tapered, as shown, whereby it may be forced up into the ring B with the result of expanding the same. On the top of this sleeve is an 30 annular flange d^2 , in the under side of which is an annular groove d^3 , whose outer wall d^4 is tapered complimentarily to the conical wedge b^5 , with which it is intended to engage.

The rod E , upon whose upper end is an 35 ejector-plate e , passes loosely through the sleeve D . Below the sleeve D is a collar e' , which is adapted to engage with the lower end of the sleeve D . A coiled spring J , which surrounds the rod E , thrusts endwise against 40 the collar e^3 or some other shoulder on the rod and against a fixed plate L , through which the rod passes loosely, whereby the spring exercises a continuous force to move the rod E upward. The extent of this upward movement is regulated by an adjustable stop-nut 45 e^2 below the plate L .

When the die mechanism above described is in its normal position, as shown in Fig. 8, the conical part d' of the sleeve D has been 50 forced up into the expanding ring B far enough to expand it, wherefore the flange b' extends partly over the curling-groove a' . The wire is then fed by mechanism to be presently explained through an opening a^4 in the ring A into the curling-groove a' below 55 the flange b' , where said wire substantially encircles the die. The cap R , whose lower edge is to be rolled around said wire, is shown in Fig. 8. It is made of thin sheet metal and 60 has a flange r , in whose lower edge a substantially vertical slot r' is formed. This cap is placed flange downward upon the ejector-plate e , the lower edge of said cap entering the ring A , the notch r' in said flange being 65 placed directly above the part of the wire which is passing through the slot a^4 in the said ring A . The plunger then comes down,

forcing the cap downward, whereby the lower edge of said cap is by its engagement with the groove a' caused to roll inward and around the wire, the flanges b' on the expanding ring-section holding the wire down, so that the edges of the cap will be rolled around it. The ejector-plate e and the rod E , which it is attached to, are likewise forced down, the ejector-plate engaging with the sleeve D and forcing it down, whereby the beveled surfaces d^4 engage with the conical surfaces b^5 on the ring-segments, thereby drawing said segments inward and contracting the ring B . 70 When the plunger begins its upward movement, the spring J forces the rod E upward, and the first effect of this movement is to lift the wired cap above the flanges b' to the ring-segments. The nut e' then engages with the 75 sleeve D and pushes it up, whereby the beveled shoulders d' on the sleeve engage the ring-segments and force them outward—that is to say, expand the ring B . The parts referred to have now completed the cycle of 80 their movements and are in their normal positions again.

The mechanism for feeding the wire into the die and cutting it off will now be described. The wire S passes between two 85 grooved rollers H H' , by which it is forced through a hole i in a guide-block I , thence through a horizontal notch g' in the vertical arm g of the pivoted cut-off lever G , and finally through the slot a^4 in the ring A into 90 the die below the flange b' on the expanding ring. These rollers are secured to shafts h and h^3 , which are mounted in suitable bearings, and to these shafts are secured the meshing pinions h' , whereby the revolution 95 of one roller is necessarily accompanied by a revolution of the other roller in the reverse direction. The lower shaft h is revolved through a pinion h^2 , loosely mounted thereon and clutched thereto at the proper times by 100 a mechanism to be presently explained. A rocking gear-segment F engages with the pinion h^2 . This segment is caused to rock by a connecting-rod f' , which engages at its ends with a crank-pin f^2 on an arm f , secured to 105 the gear-segment, and a crank-arm k , secured to a shaft K , on which the pinion k' is secured. This pinion k' is oscillated by a vertically-movable rack-bar P , which is moved in suitable guides p' by a cam-groove m in the face of a 110 disk M , secured to the shaft Z , and a pin p^2 on the rack-bar, which enters said groove. The upper end of the rack-bar has a vertical slot p^3 , which embraces the shaft, whereby it is compelled to move vertically. The cam-groove m is of such shape that it quickly draws 115 the rack-bar up during about one-fourth of its own revolution. During this movement of the rack-bar the plunger is coming down and is nearing the end of its stroke. The pinion h^2 is at this time clutched to the shaft h . This movement of the rack-bar transmitted through the intermediate mechanism described causes the rotation of the feed-roller 120 125 130 135

in the feeding direction, whereby said wire is fed into the die as before explained. When the wire has been pushed around the die, it will be in contact with the wall of the ring A—that is to say, the diameter of the wire loop in the die will be as great as possible. Just before the plunger, however, reaches its lower point the cam *m* suddenly reverses its curve and moves the rack-bar down a short distance, which reverses the movement of the feed-rollers, whereby they pull backward on the wire sufficiently to draw the wire into contact with the inner edge of the groove *a*. Previously to being so drawn inward the wire offers an obstacle to the downward movement of the lower end of the cap-flange *r*, which obstacle is withdrawn by this movement of the wire. At this instant the plunger forces the cap-flange down between the wire and the ring A, and thereafter finishes its work of rolling the edges of said flange, as before stated. At this instant the pinion *h*² is also unclutched from the shaft *h*, wherefore as the rack-bar continues its downward stroke under the influence of the cam *m* the feed-rollers remain idle. When the rack-bar begins its upward movement, as before explained, this pinion *h*² is automatically clutched to the shaft *h*, and the described operation is repeated.

The wire-cut-off lever *G* has a vertical part *g*, which is pivoted on a vertical axis to the ring A, a part of which has been cut away to accommodate this cut-off. In the outer face of this vertical part of the cut-off device is a horizontal notch *g'*, into which the wire *S*, pushed through the wire-guide, enters and is guided against vertical movement as it enters the notch *a'* in the ring A. This cut-off device has also a horizontal arm *G*, to which a connecting-rod *g* is pivoted, the other end of this connecting-rod being connected by a universal joint with an arm *g'*, which is fast on the shaft *Q*, to which the pinion *q*² is secured. A vertically-movable rack-bar *T* engages with this pinion *q*², and its vertical movement in suitable guides is produced by a cam-groove *n* in the face of the disk *N*, secured to the shaft *Z*, and a pin *t* on the rack-bar entering this groove. This rack-bar is slotted at its upper end and embraces the shaft *Z*. Just as the downward movement of the plunger is being completed this cam-groove suddenly reverses its curvature, as at *n'*, and draws the rack-bar upward, which results through the intermediate mechanism in swinging the cut-off device around, so that the wire is sheared off between the cut-off and the wire-guide, and the wire is bent around into an approximate radial position. The cam then reverses its curvature, and this cut-off is swung slowly back to its original position, in which it is held while the wire is being fed forward. The bent end of the wire is freed from the cut-off during the first part of this return movement, wherefore the cap *R* may be removed, as described.

I will now describe the mechanism for clutching and unclutching the pinion *h*² and the shaft *h*. This pinion, which is loosely mounted on the shaft *h*, is secured to a disk *h*⁴. Two ratchet-wheels *U* *W*, whose teeth face in opposite directions, are rigidly fastened to this shaft *h* adjacent to this disk and between it and a disk *V*, having a sleeve *v*, which is loosely mounted upon the shaft. A spring-pawl *u'*, pivoted to the disk *h*⁴, engages with the ratchet *U*, whereby the pawl when moved in one direction causes the ratchet to move, and consequently causes the shaft *h* to move. When this pinion *h*² is revolved in the reverse direction, this pawl slips over the teeth of the ratchet *U*. Another pawl *w* is pivoted to the same disk *h*⁴, or rather to an extension-plate *h*⁵, secured to said disk, and it engages with the other ratchet *W* under certain circumstances. In this pawl is an inclined slot *w'*, which receives a pin *v'*, secured or made fast to the other disk *V*. Around the sleeve *v*, of which this last-named disk is a part, is a friction-brake *O*, which is itself immovable, being attached to the bed-plate *X* and which embraces the sleeve with sufficient force to retard its movement. When the pinion *h*² has its direction of motion suddenly reversed after the wire has been fed into the die, the pawl *w* is in engagement with the ratchet, and consequently the ratchet is revolved, and so, also, are the shaft and feed-rollers, but in the direction reverse to the feeding direction. When the pinion thus reverses its direction of movement, the friction-brake *O* retards the movement of the sleeve *v*, wherefore the disk *h*⁴, which carries the pawl *w*, rotates, while the disk *V*, which carries the pin *v'*, does not rotate. The inclined slot *w'* in the pawl *w* coacts with the pin, causing the pawl to be drawn outward and to become disengaged from the ratchet, wherefore the rotation of the shaft *h* ceases. Then the end of the slot *w'* engages with the pin *v'*, and this causes this friction-held disk to rotate with it. When the pinion *h*² reverses its movement, the pawl *w* rotates with the disk *U*, but the sleeve *v* is again held by the brake until the other end of the slot in the pawl engages with the pin, after which said sleeve *v* rotates with the pawl. The pin *v'* in passing from one end of the slot *w'* to the other forces the pawl inward into engagement with the ratchet, where it is ready to repeat the operation before explained.

Having described my invention, I claim—

1. The combination with a plunger of a die composed of a pair of coöperating rings which have on their proximate faces an annular rib on one ring and a flange on the other, one of said rings having independently-movable sections whereby it is adapted to approach or recede from the other ring, a sleeve movable axially in relation to such expanding ring and carrying inclined surfaces adapted to operate upon the ring-sections and move them out or in as it moves in one direction or the other,

a rod independently movable through said sleeve, a shoulder on said rod adapted to limit the independent movement of the rod through the sleeve and cause the sleeve to move with it, a plate moving with said rod and adapted to support an article similar to a can-cover in position to be acted upon by said die, and means for causing said plate to move said article away from said die, substantially as and for the purpose specified.

2. The combination of an outer ring having an internal annular rib which has a curling-groove in its side, and an expanding ring within the outer ring, and made up of independently-movable sections, each having a flange adapted to extend over said rib, with a sleeve movable axially through said expanding ring carrying inclined surfaces adapted to engage with the ring-sections to move them out or in as it moves in one direction or the other through said expanding ring, a rod movable through the sleeve, an ejector-plate on the end of the rod and a shoulder on said rod on the other side of said sleeve, and a spring adapted to move the rod in one direction, substantially as and for the purpose specified.

3. The combination of an outer ring A having an internal rib a in which a curling-groove a' is formed, an inner ring within this outer ring, said inner ring being expandible by means of movable sections, each section having, first, a flange adapted to extend over said rib and hold a wire in the curling-groove, and, second, a conical surface on its upper side, with a sleeve which passes axially through said expanding ring and has beveled surfaces for engaging with the ring-sections to move them outward and inward, a longitudinally-movable rod passing through said sleeve, an ejector-plate on the end of said rod, and a shoulder on the rod on the other side of said sleeve, and a reciprocating plunger above said ejector-plate, substantially as and for the purpose specified.

4. The combination of the ring A having the internal annular rib a with a curling-groove a' in its upper side and an expanding ring made up of independently-movable sections, each of which has, first, an external flange adapted to extend over the rib a and to hold a wire in said groove, and, second, the beveled surface b^5 , with the sleeve D which passes axially through the expanding ring and has, first, a beveled shoulder d' , second, a reduced neck d , and, third, a flange d^2 with the beveled surface d^4 on its under side, a rod E movable through said sleeve, having an ejector-plate on its end above the sleeve and a shoulder below the sleeve, and a spring for moving said rod upward, and a movable plunger, substantially as and for the purpose specified.

5. The combination of a fixed ring having an internal annular rib which has a curling-groove in its upper side, an expanding ring made up of independently-movable sections each having a flange adapted to extend over said rib, and means for preventing longitudi-

nal movement of said ring-sections, with a sleeve movable axially through said expanding ring and carrying inclined surfaces for moving the ring-sections out or in as it moves in one direction or the other, a rod movable through the sleeve, an ejector-plate on the end of said rod, a shoulder on said rod below said sleeve, a spring for moving the rod in one direction, and a press-plunger for moving it in the opposite direction, substantially as and for the purpose specified.

6. The combination of a ring having an internal annular rib with a curling-groove in its upper side, an expanding ring made up of independent sections each having a flange adapted to extend over said rib, radial guidepins secured to and radial holes formed in the outer ring and the co-operating ring-sections whereby said sections are caused to move in radial directions, with a sleeve movable axially through said expanding ring carrying inclined surfaces for moving the ring-sections out or in as it moves in one direction or the other, a rod movable through the sleeve, an ejector-plate on the end of said rod, a shoulder on said rod on the other side of said sleeve, a spring for moving the rod in one direction, and a reciprocating plunger for moving it in the opposite direction, substantially as and for the purpose specified.

7. The combination of a ring A, secured upon the bed-plate of the press beneath the plunger thereof, and having the internal annular rib with a curling-groove in its upper side, and an expanding ring composed of independent sections each having, first, two external flanges adapted to project above and below said rib, and, second, the conical surface b^5 , the sleeve D having, first, a reduced neck, second, beveled shoulders, and, third, an end flange with an inclined surface on its under side, a rod movable through said sleeve, an ejector-plate secured thereto above the sleeve, a shoulder on the rod below the sleeve, a spring for moving the rod upward, and a reciprocating press-plunger for moving it downward, substantially as and for the purpose specified.

8. The combination of a wiring-die which includes an outer ring having an internal annular rib with a curling-groove on its side, said ring having an opening through it entering said groove, an expanding ring having separable sections each of which has an external annular flange adapted to extend over the said curling-groove, means for expanding and contracting said ring, with wire-feeding mechanism adapted to feed a wire into said groove and mechanism for cutting off the wire and bending its end outward, substantially as and for the purpose specified.

9. The combination of a wiring-die, which includes an outer ring having an internal annular rib with a curling-groove on its side, said ring having an opening through one side, and an expanding ring made up of separable sections each having an external flange,

- and mechanism for expanding and contracting said ring, with wire-feeding mechanism, a wire-guide, and a cut-off device pivoted on a vertical pivot and having a horizontal notch 5 through which the wire passes in going from said wire-guide to said opening, and means for oscillating said cut-off on its axis, whereby it cuts off the wire and bends its end outward, substantially as and for the purpose specified.
10. The combination of the coöperating parts of a die adapted to curl the edge of an article similar to a can-cover around a wire, and mechanism for pushing such wire into one of such die parts and then pulling it back 15 slightly to draw it out of the way of the edge to be curled, and mechanism for cutting off the wire, substantially as and for the purpose specified.
11. The combination of a ring A having the 20 internal annular rib *a* with a curling-groove *a'* in its upper side, an expanding ring made up of sections each of which has an external flange which extends over said rib whereby to hold a wire in said groove, and mechanism 25 for expanding and contracting said ring, with wire-feeding mechanism which pushes a wire through an opening in the ring A into said curling-groove, and around said ring and then pulls back upon said wire to tighten it 30 in said groove, and a plunger for forcing a cap down in said ring A whereby its edge is curled around said wire, substantially as and for the purpose specified.
12. The combination, with an outer part of 35 a die having an internal annular rib with a curling-groove on its side, an opening from the outside of the die to said groove, an internal expanding ring having separable sections which have external flanges coöperating 40 with said curling-groove, mechanism for holding said inner ring in its expanded position, mechanism for then pushing a wire into said curling-groove and around the same and for 45 then drawing back on said wire slightly, mechanism for forcing an article similar to a can-cover into said die and causing its edge to curl around said wire, mechanism for cutting off said wire, and mechanism for contracting said inner ring to release the article 50 wired, substantially as and for the purpose specified.
13. In a cap-wiring apparatus, the combination of a wiring-die having an external ring A with an opening through its wall, wire-feeding rolls, and a wire-guide, with a cut-off device pivoted on a vertical axis between the 55 end of the wire-guide and the opening in the ring, said cut-off device having a horizontal slot through which the wire passes from the 60 guide to the slot, and means for turning said cut-off on its axis to cut off the wire and bend it outward, substantially as and for the purpose specified.
14. In a cap-wiring apparatus, the combination of a wiring-die having an external ring A with an opening through its wall, wire- 65
- feeding rolls, and a wire-guide, with a cut-off device pivoted on a vertical axis between the end of the wire-guide and the opening in the ring, said cut-off device having a horizontal slot 70 through which the wire passes from the guide to the opening, said cut-off device having a horizontal arm, a cam, a rack-bar movable thereby, a pinion engaged by said rack-bar, a crank-arm rigidly connected with said 75 pinion, and connections between said cut-off arm and crank-arm, substantially as and for the purpose specified.
15. The combination of an outer ring having an internal annular rib which has a curling-groove in its side, an expanding inner ring having independently-movable sections which have flanges adapted to extend above said rib and flanges adapted to extend below 80 said rib and flanges adapted to extend below said rib and thereby prevent longitudinal 85 movement of the ring-sections, and radial guide-pins and coöperating radial holes carried by the outer ring and the movable ring-sections whereby said sections are allowed to move in radial directions, and means for expanding said inner ring, substantially as and for the purpose specified.
16. A die for curling the edge of a metallic article similar to a can-cover around a wire, which consists of an outer member having 95 an internal curling-groove and an inner expanding member having a flange adapted to extend oversaid groove, combined with mechanism for placing a wire in such curling-groove and for drawing the same under the said flange 100 and thereby out of the way of the article to be curled, and mechanism for holding said expanding ring in its expanded position while the article is being curled, and for thereafter contracting it, and mechanism for forcing 105 said article into the die to curl its edge around the wire, substantially as and for the purpose specified.
17. A die for curling the edge of a metallic article similar to a can-cover inwardly around 110 a wire, which consists of an outer member having an internal curling-groove and an inner expanding member having a flange adapted to extend over said groove, combined with mechanism for pushing a wire around the 115 curling-groove, mechanism for cutting off said wire some distance from the article in the die and for turning this projecting end outward, mechanism for holding the expanding member in its expanded position while 120 the article is being curled, and for thereafter contracting it to release said wired article, and mechanism for forcing said article into the die to curl its edge inward around the wire, substantially as and for the purpose 125 specified.
18. The coöperating parts of a die adapted to curl the edge of an article similar to a can-cover around a wire, one of said die parts adapted to carry a wire tending to lie in the 130 path of the edge of the article to be wired as the two are brought toward each other, com-

combined with mechanism for moving such wire out of the way of said edge to be curled, substantially as and for the purpose specified.

19. The combination of the coöperating parts of a die adapted to curl the edge of an article similar to a can-cover around a wire, and mechanism for shoving such wire into one of the die parts, and mechanism causing such wire to be pulled slightly backward after

it is in the die to move it out of the way of the edge to be curled, substantially as and for the purpose specified.

In testimony whereof I hereunto affix my signature in the presence of two witnesses.

HERBERT H. HULL.
